SELF-IGNITING ATTACHMENT AND METHOD OF MAKING THE SAME

Filed May 21, 1943

Inventor: Bernard D. Haber

UNITED STATES PATENT OFFICE

2,370,306

SELF-IGNITING ATTACHMENT AND METHOD OF MAKING THE SAME

Bernard D. Haber, Dayton, Ohio

Application May 21, 1943, Serial No. 487,874

11 Claims. (CL 131—7)

The present invention relates to self-igniting attachments, in particular for use in connection with cigarettes, cigars or the like. Heretofore, it was generally necessary to use a match or a lighter for lighting cigarettes or cigars. Aside from the inconvenience of carrying matches or lighters, these lighting devices were not quite satisfactory when the cigarette or cigar was to be lighted in stormy or similar weather.

It is an object of the present invention to overcome the above-mentioned drawbacks.

It is another object of this invention to provide means adapted to form an integral unit with cigarettes or cigars which will make it possible easily to light a cigarette or cigar without any additional means.

It is a further object to provide a lighting attachment to be connected with the cigarette or cigar, which comprises self-igniting or pyrophoric material normally held in an inactive condition but adapted to be made effective at any desired time by exposing it to air.

It is also an object of the present invention to provide a method of making capsules containing a self-igniting material such as pyrophoric metal, which capsules may easily be connected to slow-burning material and while normally holding the self-igniting material in ineffective condition, may easily and manually be handled so as to cause self-lighting material to inflame the said slow-burning material.

These and other objects and advantages of the invention will appear more clearly from the following specification in connection with the accompanying drawing in which:

Figure 1 illustrates in perspective a capsule according to the invention in connection with a cigarette.

Figure 2 is an enlarged section along the line 2—2 of Figure 1.

Figure 3 is an enlarged section along the line 3—3 of Figure 1.

Figure 4 shows on an enlarged scale a developed top view of the capsule according to the invention.

Figure 5 shows the invention in connection with a cigar.

Referring now to the drawing in detail, Figure 1 shows a cigarette 10 having connected to one end thereof a capsule according to the invention, which capsule is generally designated 11. This capsule comprises a cup shaped bottom, part 12, a flanged part 13 and a top part 14. The cup-shaped part 12 contains self-igniting material 15, i. e., material which, when exposed to oxygen or

oxygen-containing gases such as air, will ignite. Materials of this kind are well-known and may be of any desired type, for instance of the group called the pyrophoric metals, such as pyrophoric iron, pyrophoric lead, etc. Such materials are usually kept in alcohol, in which state they are inert. The flanged part 13 is engaged by, and in an airtight manner connected to the top part 14, which may be of any desired shape suitable for connection with the element, the lighting or igniting of which is desired. It is preferable to place the self-igniting material in the capsule 11 in wet condition, i. e., when still permeated with alcohol, and then quickly to seal the capsule by placing the top part 14 upon and connecting the same in an airtight manner to the cup-shaped bottom part 12. If desired, however, any other means may be employed for preventing a premature ignition of this self-igniting material in the capsule.

In the specific example, shown in the drawing, the top part 14 is provided with two connecting flaps 16, which are adapted to be glued or otherwise connected to the cigarette end. The top part 14 is furthermore provided with a tongue 17, adapted to be manually grasped and torn off the capsule so as to expose the self-igniting material 15 to air. The capsule may be made of any desired material which is adapted to normally prevent the access of air to the self-igniting material, while, on the other hand, allowing at any desired time a partial destruction of a part of the capsule so as to cause access of air to the self-igniting material for the ignition thereof. Furthermore, that portion of the capsule 12, which contains the self-igniting material 15, must be inflammable so as to allow the ignited material to contact the slow-burning material mentioned above, for instance the tobacco of a cigarette. Preferably, the cup-shaped portion 12 of the capsule is made of thermoplastic inflammable material, whereas the top portion 14 is preferably made of airtight material which normally has great resistance against tearing, but, once tear is started, loses this resistance. Such material is, for instance, the material normally known under the trade mark "Cellophane."

In order to enable an easy removal of a portion of the top part 14, to expose the material 15 to air, the top part 14 is slightly torn at 18. This, however, will, under normal conditions, not allow the access of air to the material 15, since, as mentioned above, the flange 13 is airtight and glued or otherwise connected to the top part 14. The fact that the top part 14 is

torn in at 18 will materially facilitate the further tearing of the top part 14 and thereby the exposure of material 16 to air when such exposure is desired.

It is understood, of course, that the materials to be used are not poisonous both singly and in combination.

It is further understood that the invention is by no means limited to the particular shape of the capsule shown in the drawing, but that it also comprises any modifications within the scope of the appended claims.

What I claim is:

1. A self-igniting attachment for use in connection with cigarettes or cigars, comprising in combination a container, self-igniting material arranged in said container and adapted, when brought into contact with air, to ignite, means associated with said container for normally preventing the access of air to said self-igniting material, and connecting means for connecting said container with the cigarette or cigar.

2. In combination, a cigarette or cigar, a capsule connected to one end of said cigarette or cigar, said capsule comprising material adapted to ignite when brought into contact with air, said capsule also comprising means normally preventing access of air to said material but being adapted to be removed manually for allowing said access of air, and means of fastening said capsule to said cigarette or cigar.

3. A method of making a self-igniting attachment for use in connection with cigarettes or cigars, which comprises the steps of preparing a cup-shaped container, having an inflammable bottom portion, placing in said container material adapted to ignite when brought in contact with air, and closing said container in an airtight manner to normally prevent access of air to the material in said container.

4. A self-igniting attachment for use in connection with a cigarette or cigar, comprising in combination a container having a cup-shaped portion of inflammable material, self-igniting material arranged in said cup-shaped portion and adapted, when brought into contact with air, to ignite, and sealing means connected to said cup-shaped portion of the container for sealing said self-igniting material against access of air, said sealing means being adapted manually, at least partially, to be detached from said container.

5. A self-igniting attachment for use in connection with cigarettes or cigars, comprising in combination a container having extensions for connection with a cigarette or cigar, self-igniting material adapted to ignite when brought into contact with air, said material being arranged in said container and being normally protected against contact with the air, and means connected to said container and operable manually for exposing said self-igniting material to air.

6. A self-igniting attachment for use in connection with cigarettes or cigars comprising in combination a container and self-igniting ma-

terial arranged in said container, said material being adapted to ignite when exposed to air, said container having a bottom portion housing said self-igniting material and being made of inflammable material, and a top portion connected to said bottom portion in an airtight manner but being adapted to be operated manually for permitting access of air to said self-igniting material.

7. In combination, a cigarette or cigar, a container having a cup-shaped portion imbedded in said cigarette or cigar and connected thereto, and self-igniting material arranged in said container, said container having means connected to said cup-shaped portion and normally protecting said self-igniting material against contact with air, said last mentioned means also being adapted manually to be actuated for admitting air to said self-igniting material to bring about ignition thereof.

8. In combination, a cigarette or cigar, container means connected to one end of said cigarette or cigar and containing sealed therein material, adapted, when brought into contact with air, to ignite, at least a portion of said container means being inflammable, and means connected to said container means and manually operable for admitting air to said material in said container means to cause ignition of said material.

9. A method of making a self-igniting attachment for use in connection with cigarettes or cigars, which comprises the steps of preparing container means having an inflammable bottom portion, sealing self-igniting material in airtight manner in said container means, providing said container means with an element operable manually to break the seal of said container means, and providing said container means with connecting means for attachment to a cigarette or cigar.

10. A method of making a self-igniting attachment for use in connection with cigarettes or cigars, which comprises the steps of preparing a cup-shaped element of inflammable material, placing self-igniting material in said element while the material is permeated with alcohol, covering said cup-shaped member by a cover, and sealing said cover to said cup-shaped member, and providing said cup-shaped member with means for connecting the same to a cigarette or cigar.

11. A self-igniting attachment for use in connection with cigarettes or cigars, comprising in combination container means having a bottom portion of inflammable material, a self-igniting material sealed in said container means in an airtight manner and adapted when contacted by air to ignite, and means associated with said container means for connecting the latter to a cigarette or cigar, said container means having a top portion with a flap of tear-resistant material adapted to lose this tear-resistance once it has been slightly torn.

BERNARD D. HABER.
